INVENTOR
Gordon Earl
BY Edward Taggart

His ATTORNEY

UNITED STATES PATENT OFFICE.

GORDON EARL, OF PIERSON, MICHIGAN.

SHINGLE-SAWING MACHINE.

SPECIFICATION forming part of Letters Patent No. 298,737, dated May 20, 1884.

Application filed April 8, 1884. (No model.)

To all whom it may concern:

Be it known that I, GORDON EARL, a citizen of the United States, residing at Pierson, in the county of Montcalm and State of Michigan, 5 have invented certain new and useful Improvements in Shingle-Machines, of which the following is a specification.

My invention relates to the arrangement of friction-rollers in connection with the ways of 10 the tilting table of a shingle-machine; and the object of my invention is to lessen the friction between the shingle-bolt and the ways when the bolt is pushed forward against the saw, thereby diminishing the labor of the operator. 15 This object I accomplish by the mechanism illustrated in the accompanying drawings, in which—

Figure 1 is a plan view of a tilting-table saw and a portion of the frame of a shingle-machine to which my invention is applied. 20 Fig. 2 is a side view of a tilting table, showing one of the ways with friction-rollers attached thereto; and Fig. 3 is a sectional view of the tilting table on line $x x$ of Fig. 1.

25 Similar letters refer to similar parts throughout the several views.

In the drawings, A represents the saw; B and B', the end supports of the tilting table, which tilts or oscillates on journals C C' in the 30 ordinary manner, F and F' being journal-boxes in B and B'. C and C' are attached to the frame D, as shown in Fig. 1. E and E' are the ways attached to the end pieces, B and B', and with such end pieces form the tilting table. 35 The frame D is supported by the main

frame of the machine. (Not shown in the drawings.) To each way is attached a series of rollers, $a a a a$, which rollers are journaled on the journals $c c c c$. The rollers $a a a a$ project a short distance above the side pieces or 40 ways, E and E', so as to form a support for both ends of the shingle-bolt. The frame of the shingle-mill frame and the tilting table do not differ from the usual construction, except in the application to the side pieces of the 45 rollers, as above described.

The operation of my invention is as follows: The shingle-bolt being placed in the carriage, it rests on the friction-rollers, and as the carriage is pressed forward the bolt rides on the 50 rollers until the shingle is cut by the saw from the bolt. The carriage is now drawn back, the bolt passing above but not in contact with the rollers. When the carriage has been drawn back, the bolt again drops onto the rollers 55 and is again pressed forward onto the saw.

Having thus described my invention, what I claim to have invented, and desire to secure by Letters Patent, is—

In a shingle-machine, the combination of the 60 series of friction-rollers $a a a a$, turning on journals $c c c c$, the side pieces, E and E', end pieces, B and B', and journals C and C', all substantially as and for the purpose described.

65
GORDON EARL.
